Specification for Design.

Patented May 9, 1916.

Application filed November 19, 1915. Serial No. 62,432. Term of patent 14 years.

To all whom it may concern:

Be it known that I, GEORGE EDGAR BENNETT, a citizen of the United States, and a resident of Brooklyn, in the county of Kings and State of New York, have invented a new, original, and ornamental Design for Sheet-Metal Cans; and I do hereby declare the following to be a specification, reference being had to the accompanying drawing, forming part thereof, in which—

Figure 1 is a side elevation of a sheet metal can showing my new design; Fig. 2 is

a top view partially broken away of the same.

I claim:—

The ornamental design for a sheet metal can, as shown.

In testimony whereof, I, the said GEORGE EDGAR BENNETT, have hereunto set my hand.

GEORGE EDGAR BENNETT.
